CHARLES A. MORRIS, OF MONTCLAIR, NEW JERSEY.

EXCAVATING SYSTEM.

1,002,732.

Specification of Letters Patent.

Patented Sept. 5, 1911.

Application filed May 31, 1910. Serial No. 564,076.

To all whom it may concern:

Be it known that I, CHARLES A. MORRIS, a citizen of the United States, residing in Montclair, county of Essex, and State of New Jersey, have invented a certain new and useful Excavating System, of which the following is a specification.

This invention is an excavating system employing an aerial track on which travels the carriage, which supports the shovel. In systems of this type it has been customary to operate the carriage by power mechanism, but in the present invention I dispense with such mechanism and operate the carriage through the medium of the haul cable attached to the shovel.

In the system herein disclosed, the shovel may be suspended from a cable or a boom, and may be provided with either one or two haul cables, so as to be capable of loading or unloading either in one or both directions. When the shovel is hoisted and it is desired to convey the same, pull or tension is exerted on the haul cable attached to the shovel, resulting in the suspending cable forming an acute angle to the track in the direction in which the shovel is being hauled, without imparting movement to the carriage. When a certain acute angle is reached, however, depending on the load, the length of the suspending cable, the inclination of the track, etc., a further pull on the haul cable causes the carriage to travel on the track. It will thus be observed that the haul cable serves not only to load the shovel, but, also, to haul the carriage to the place of unloading.

The system permits of shovels being loaded, hauled and unloaded in one direction, and, if desired, to perform these operations, also, while moving in an opposite direction, thereby permitting the excised material to be deposited on either side of the cut, or taken from one side of the cut and deposited upon the other.

Any well known type of shovel may be employed in operating the system, but I prefer to use a shovel adapted to be loaded at either end.

In the accompanying drawings I have illustrated different practical embodiments of the invention; but the constructions

shown therein are to be understood as illustrative, only, and not as defining the limits of the invention.

Figure 1 illustrates diagrammatically a cableway equipped with mechanism for operating a shovel in either of two directions, the shovel being shown in the loading position, Fig. 2 is an elevation of part of the system shown in Fig. 1 with the shovel in a suspended and dumping position, Fig. 3 is an elevation of another embodiment of the invention wherein the carriage is adapted to travel on a boom, the shovel being adapted for loading by hauling it in either direction. Fig. 4 is a diagrammatic view of another embodiment of the invention wherein the carriage is adapted to travel upon an inclined track of a cableway so as to move in one direction on said track by the force of gravity, said system illustrating a type of shovel adapted to be loaded at one end and, after being conveyed to the point of unloading, to be discharged at the same end at which it was loaded. Figs. 5 and 6 are views in side elevation and plan, respectively, illustrating a form of shovel adapted to be loaded at either end and to be unloaded at one end only.

In Figs. 1 and 2 of the drawings I have shown a cableway embodying a cable, A, constituting an aerial track for a carriage or trolley, B, the latter being shown as having suitable wheels, b, adapted to run upon said track. As is usual in the art, the aerial track extends between, and is supported by, towers, C, positioned at the respective sides of the excavation, said towers being shown as having carrying wheels, c, adapted to run on tracks, c', whereby the position of the cableway may be shifted in the direction of the cut. It will be understood that the aerial track spans the excavation, and by employing portable towers the entire apparatus may be shifted in the direction of the length of the cut as the excavation work progresses.

Carriage, B, is shown as having direction sheaves, b', over which runs a hoisting cable, D, one end of said cable being attached to one of the towers, as at d. The hoisting cable extends from the point, d, of attachment to one tower, thence extends over one pulley,

b', of the carriage, thence downwardly to and beneath a fall block *d'*, thence upwardly from the fall block to and over another pulley, *b'*, of the carriage, thence to and 5 over a pulley, *d*², in the other tower, *C*, and thence downwardly to and around one drum, *D'*, of a series of drums, *D'*, *E'*, *F'*. Said drums are shown as being supported upon a base of one tower, *C*, and they are adapted 10 to be operated in any usual way from a motor or engine indicated generally by the reference character, *G*.

E designates an excavating shovel, one form of which is illustrated in Figs. 5 and 15 6 of the drawings, although it is not desired to limit the invention to any particular type of shovel, and for this reason I have shown a shovel of another type at *E*² in Fig. 4 of the drawings. Shovel, *E*, employed in the 20 excavating systems of Figs. 1 and 2 and Fig. 3 is, preferably, a shovel open at both ends and adapted to be loaded at either end by drawing the shovel in one direction or the other. Said shovel, *E*, is suspended 25 from fall block, *d'*, by a bail, *f*, and by a connection, *f'*, to be presently described.

F designates a haul cable which is connected with shovel, *E*, for the purpose of hauling said shovel in one direction while it 30 is in contact with the ground, thereby loading said shovel with the material. Said cable, *F*, runs over a sheave, *f*², supported in one of the towers, *C*, and the cable is adapted to be coiled upon drum, *F'*, of the 35 series of drums heretofore mentioned, whereby the cable may operate the shovel to load it. Cable, *F*, is attached directly to one end of shovel, *E*, and secured to this cable is one end of connection, *f'*, which may 40 be a chain or cable. The connection, *f'*, runs beneath a pulley or sheave, *f*³, provided on shovel, *E*, the other end of said connection being attached to fall block, *d'*. It will be noted that shovel, *E*, has a suspending 45 bail, *f*, attached thereto at or near one loading end of the shovel, while the connection, *f'*, has running engagement with the shovel and is connected by pulley, *f*³, near the other loading end of said shovel. The employment 50 of connection, *f'*, attached to cable, *F*, and co-operating with suspending bail, *f*, provides convenient mechanism for retaining the loaded shovel in a substantially horizontal position when said shovel is hoisted 55 and is being conveyed from the loading point to the spoil bank or other place where the shovel is to be unloaded. During the operation of hoisting and conveying the loaded shovel, cable, *F*, is kept under tension 60 for the purpose of precluding the shovel from tilting to an inclined dumping position, but when the load is to be discharged from the shovel, tension is relaxed on cable, *F*, whereupon the connection, *f'*, runs beneath sheave, *f*³, and the shovel is 65

free to swing downwardly to an inclined position, substantially as shown in Fig. 2, thus discharging the load by gravity from the shovel.

When my invention is embodied in a shovel adapted to be loaded at either end, I employ a cable, *E*³, in addition to cable, *F*. Said cable, *E*³, is attached to the other end of shovel, *E*, from that end to which cable, *F*, is connected, said cable, *E*³, extending 75 from the shovel in an opposite direction to cable, *F*, see Fig. 1. The cable, *E*³, passes around a sheave, *e*³, supported in the left hand tower, from said sheave cable, *E*³, runs across the excavation above the aerial track 80 cable, *A*, and over a sheave in the right hand tower, *C*, and is finally coiled upon one of the operating drums of the series, said drum being indicated at *E'*. It will be understood that the drums, *D'*, *E'*, *F'*, are to 85 be operated independently or jointly as may be demanded by the conditions of service, but in the construction of Figs. 1 and 2, it is essential that when cable, *F*, is coiled on drum, *F'*, to haul shovel, *E*, in one direction, 90 cable, *E*³, should be paid out or uncoiled from drum, *E'*, and contrariwise, when tension is placed on cable, *E*³, by coiling it upon drum, *E'*, cable, *F*, should be paid out by 95 uncoiling it from drum, *F'*, with this distinction, however, that should the loaded shovel be hoisted above the ground and hauled toward the left in Fig. 1 by the operation of cable, *E*³, sufficient tension must be kept on said cable, *F*, to preclude premature 100 dumping of the load.

In Figs. 5 and 6 of the drawings, I have illustrated a practical construction of shovel, *E*, adapted to be loaded at either end by hauling it in one direction or the other. Said shovel is shown as consisting of a bottom, *e*¹, and side walls, *e*². The shovel is provided at its respective ends with reinforcing bands, *e*³, see Fig. 5, and across the top of the shovel are bridge pieces, *e*¹⁰, *e*¹¹, operating as stays for the sides of the shovel. The shovel is closed at its bottom and two sides, but it is open at the two ends thereof and at the top. Haul cable, *F*, is attached by suitable chains, *e*⁵, to one end portion of the shovel, whereas the other haul cable, *E*³, is attached by chains, *e*⁶, to the other end portion of the shovel, said chains, *e*⁵, *e*⁶, being shiftable up or down on the respective end portions of the shovel for the purpose of 110 regulating the depth of the cut. The suspending bail, *f*, is attached to the respective side portions of the shovel near one end thereof. The flexible connection, *f'*, runs over and in contact with a pulley, *f*², on the bridge bar, *e*¹⁰, and below and in contact with a pulley, *f*³, on the other bridge bar, *e*¹¹, the upper end of said flexible connection, *f'*, being attached to the fall block, as heretofore described. The pulley, *f*², is provided 115 120 125 130

for the purpose, mainly, of precluding cutting of flexible connection, f' , when the shovel is being dumped.

The operation of the system shown in Figs. 1 and 2 is as follows: Assuming that carriage, B, is over the cut, cables, D, F and E^3 , are slackened and shovel, E, is lowered into contact with the ground. For cutting in one direction and loading the shovel at one end thereof, cable, E^3 , is slackened and tension is applied to cable, F, by winding it upon drum, F'. The shovel having been loaded, cable, D, is operated for hoisting said shovel to the desired elevation, tension being kept upon cable, F, in order to preclude the flexible connection, f' , from running beneath sheave, f^3 , and precluding premature dumping of the shovel. For hauling the loaded shovel toward the right in Fig. 1, cable, F, is coiled on drum, F', so as to position that part of hoisting cable, D, at an acute angle to the track cable, and by continuing to coil cable, F, upon the drum, F', motion is imparted to the carriage by the pull of said cable, whereby the carriage and the loaded shovel will be drawn to the right and over the spoil bank shown in said figure. Of course, the hoisting cable should be coiled on its drum at the same time that cable, F, is coiled on drum, F', whereas cable, E^3 , should be slackened proportionately to the movement of cable, F. The carriage and shovel having been hauled to the place where it is desired to deposit the material, tension on cable, F, is slackened, thus relaxing the pull of flexible connection, f' , on one end portion of the shovel, whereupon said shovel turns to an inclined position for the purpose of discharging the load from the opposite end of said shovel to that end in which the excised material was loaded. For hauling the carriage and empty shovel back to the cut, tension is slackened on cable, F, and cable, E^3 , is operated by coiling it upon its drum, E', whereupon the pull on cable, E^3 , changes the angle of hoisting cable, D, with reference to the track, and movement is imparted to the carriage so as to return it to a position for operating. The hoisting cable is operated to lower the shovel, and the operations of cutting, loading, hoisting and conveying are resumed. For the purpose of loading the shovel at the other end by cutting in an opposite direction, tension is applied to cable, E^3 , so as to draw it toward the left in Fig. 1, and when the loaded shovel is raised by the operation of the hoisting rope, tension is kept on cable, F, to preclude dumping of the shovel. Should the loaded shovel be discharged upon the spoil bank at the right in Fig. 1, cable, F, is operated and cable, E^3 , slackened as before. Assuming, however, that it is desired to haul the loaded shovel toward the

left in Fig. 1 and dump it close to the left hand tower, the operations are as follows: The shovel is loaded and hoisted as described, and tension is kept on both cables, E^3 , F. The shovel having been hoisted to the proper height, cable, E^3 , is coiled on its drum, E', for moving the hoisting cable at an acute angle to the track and toward the left in Fig. 1, cable, F, being slackened slowly until movement is imparted to carriage, B, by the continued pull of cable, E^3 . Said cable, E^3 , is now wound on its drum, and cable, F, is unwound from its drum at practically the same speed so that cable, E^3 , will haul the loaded shovel toward the left until said shovel reaches the place where the load is to be dumped, but cable, F, keeps tension on the flexible connection, f' , during the operation of conveying the shovel. When the shovel reaches the place of deposit at the left of Fig. 1, tension on cables, F, E^3 , is slackened so that the shovel is free to drop or tilt to the position shown in Fig. 2, whereupon the load is discharged from the same end of the shovel at which it entered said shovel. The empty shovel and carriage may now be hauled back to the cut by applying tension to cable, F.

From the foregoing description taken in connection with the drawings it is apparent that cable, F, operates to load the shovel at one end, to impart movement in one direction to the carriage when the loaded shovel is suspended therefrom, and to control the dumping of said shovel. Furthermore, cable, E^3 , operates to load the shovel at its other end and to haul the loaded shovel and carriage in an opposite direction, thus permitting the shovel to be hauled in one direction or other and to be loaded in the direction in which it is hauled. The cables, F, E^3 , and hoisting cable, D, are all the cables required for operating the shovel under certain conditions, but there may arise conditions in the operation of carriage, B, which render it necessary to lock or grip the carriage on the aerial track during the operations of loading the shovel or dumping the shovel, or of both loading and dumping the shovel. For example, when the carriage and shovel are moved quite close to one tower or the other, the inclination of the aerial track may be such that the shovel cannot be unloaded easily and quickly, and at this time I find it desirable to employ means for retaining the carriage in substantially fixed relation to the track during the operation of dumping the shovel.

Various mechanical expedients may be resorted to for retaining the carriage in substantially fixed relation to the aerial track, substantially as disclosed in a prior application filed by me on April 29, 1909, Serial No. 492,882. One embodiment of means for

retaining the carriage in position is diagrammatically shown in Fig. 1, wherein H designates a grip supported in the carriage and adapted for engagement with cable track, A. This grip is operated by cable, H', one end of which is attached to the left hand tower. Said cable passes beyond gripping mechanism, H, to the right hand tower, and over a pulley or sheave, h, therein, said grip operating cable being connected with a lever, h', at the power plant. When the lever is moved to operate cable, H', the grip is adjusted to release the carriage and permit the load and carriage to be moved in one direction or the other by cables, F or E³, respectively, but the carriage and shovel having been moved to a position over the place where the load is to be discharged, the grip operates to make the carriage fast with the aerial track, A, whereupon the cable, F, may be relaxed and the shovel dumped.

In Fig. 3 of the drawings I have illustrated an excavating system embodying the same general principles as the systems of Figs. 1 and 2. In lieu of a cable, A, to form the aerial track I employ a boom, A', supported on a tower, C', and extending over the excavation. On the aerial track formed by boom, A', is adapted to travel the carriage, B', having sheaves for a hoisting cable, D', one end of said cable being attached to the outer end of the boom. The hoisting cable has a shovel, E, suspended therefrom, and to this shovel are attached cables, F, E³. The shovel shown in Fig. 3 is similar to the shovels of Figs. 1, 2, 5, and 6, and said shovel is controlled by the flexible connection, f'. Cable, F, extends to an operating drum, F', cable, E³, extends around a pulley, e⁶, at the outer end of the boom and thence over a pulley, e⁷, to operating drum, E', and hoisting cable, D, extends to a winding drum, D', by which the shovel may be raised and lowered. In the excavating system employing a boom it is not necessary to use means for locking the carriage on said boom, but in other respects the system of Fig. 3 is constructed and operated as hereinbefore described.

The excavating system illustrated in Fig. 4 embodies an aerial track formed by a cable, A², one end of which is attached to an anchorage, I, of the kind known in the art as a "dead man". Said aerial track, A², occupies an inclined position over the cut, the higher end of the cable being supported in a tower, C². Carriage, B², is fitted to the aerial track to run in one direction by gravity, but said carriage and the load are adapted to be hauled in an opposite direction by cable, F. The carriage is equipped with the sheaves for guiding hoisting cable, D⁵, one end of which is secured to anchorage, I. Said hoisting cable has the fall block, d', and it runs to the right from the carriage

over a sheave, d², in the tower and is coiled upon a drum, D'. Shovel, E², is of the usual type adapted to be loaded at one end and to be unloaded at the same end, and in this form of the invention, said shovel is closed at the rear end and open at its front loading and unloading end. The shovel is shown as suspended by a bail, j, connected to fall block, d', and said bail or fall block is shown as having a sheave, j', over which runs a flexible cable or chain, J, one end of which is attached to haul cable, F, and the other end to shovel, E², near the front end thereof. In operation the system of Fig. 4 requires means for locking carriage, B², on the inclined cable track, and this retaining or locking mechanism may be the grip, H, and cable, H', of Fig. 1, but, preferably, said retaining mechanism is embodied in an endless cable, K, and a friction drum, K', for controlling said endless cable, all as disclosed in my Patent No. 949,961, granted February 22, 1910. The carriage controlling cable has one end attached to carriage, B, then extends toward the left around a sheave, k, attached to anchorage, I, thence extends to the right and over drum, K', and thence extends back to the carriage so that the respective ends of cable, K, are attached to said carriage. With drum, K', is associated a friction brake or other locking mechanism for restraining said drum from rotation, as disclosed in said prior patent, but when the carriage is hauled in one direction or the other the friction brake should be relaxed to permit drum, K', to turn freely, whereupon cable, K, is operated by the movement of the carriage.

In operation shovel, E², is lowered into contact with the ground and tension is applied to cable, F, for the purpose of loading the shovel. The loaded shovel is hoisted by the operation of cable, D⁵, and tension is kept on cable, F, to preclude dumping of the load. By winding said cable, F, upon its drum, F', the loaded shovel and hoisting cable are moved at an acute angle to the track, and the pull of said hoisting cable moves the carriage and the loaded shovel to a position over the spoil bank. The brake is applied to friction drum, K', to restrain cable, K, from movement and to return the carriage in a fixed position, and by relaxing tension upon cable, F, the flexible connection, J, allows the shovel to tilt to a dumping position. By releasing drum, K', and cable, F, the carriage and shovel are adapted to descend by gravity along the inclined aerial track, A², but when the carriage reaches the place where the shovel is to be loaded, drum, K', is held from rotation, and the carriage is retained in position by endless cable, K.

While I have shown and described the system as adapted for excavating work, it is

apparent that the apparatus may be used for other purposes, and I do not, therefore, intend to limit the use of the apparatus to the work of digging and excavating.

5. Having thus fully described the invention, what I claim as new, and desire to secure by Letters Patent is:

1. In an excavating system, a track, a carriage adapted to travel thereon, a fall rope adapted to be held out of vertical alinement during the travel of the carriage, a shovel suspended by the fall rope from said carriage, and a haul rope attached to the shovel for loading the same, for exerting a 10 pull on the shovel without imparting movement to the carriage (whereby the said shovel is thrown out of vertical alinement with the carriage), and for imparting movement to said carriage and shovel while thus 15 suspended in any desired position below the carriage, and a haul rope attached to the shovel and adapted to impart movement to the carriage and shovel while the haul rope is inclined at an angle to the line of travel 20 of the carriage.

2. In an excavating system, a track, a carriage adapted to travel thereon, a fall rope, a shovel suspended by the fall rope from the carriage and adapted to be hauled while suspended in any desired position below the carriage, and a haul rope attached to the shovel and adapted to impart movement to the carriage and shovel while the haul rope is inclined at an angle to the line of travel 25 of the carriage.

3. In an excavating system, a track, a carriage adapted to travel thereon, a fall rope, a shovel suspended by the fall rope from the carriage, a haul rope attached to the shovel for imparting movement to the carriage and shovel and a cable coöperating with the haul rope and shovel so as to preclude dumping of the shovel during the 35 movement of said carriage and shovel.

4. In an excavating system, a track, a carriage adapted to travel thereon, a fall rope, a shovel suspended by the fall rope from the carriage and adapted to travel at any desired position below the carriage, 40 means for retaining the carriage against movement upon said track, and a haul rope attached to the shovel and operating to impart movement to the shovel for loading the same and, also, to impart movement to the 45 shovel and to the carriage when said shovel is raised by the fall rope to a position below the level of the track and out of contact with said carriage.

5. In an excavating system, a track, a carriage adapted to travel thereon, a fall rope, a shovel connected to the fall rope and adapted to be suspended thereby in a desired position substantially below the level 55 of said track, a haul rope connected to the 60 shovel for imparting movement thereto so as to load it, for imparting movement to the

shovel and the carriage when said shovel is elevated, and a cable coöperating with the haul rope and shovel so as to preclude dumping of the shovel when suspended in 65 a raised position.

6. In an excavating system, a track, a carriage adapted to travel thereon, a fall rope, a shovel connected to the fall rope and adapted to be suspended therefrom, a haul 70 rope connected to the shovel and operating to impart movement to the shovel and the carriage when said shovel is loaded and is suspended, and means coöperating with the shovel and the haul rope for precluding 75 dumping of the suspended shovel, said means being operated by the tension of the haul rope while imparting traveling movement to the carriage and the shovel.

7. In an excavating system, a track, a carriage adapted to travel thereon, a shovel adapted to be loaded at either end, a fall rope for the shovel, a rope attached to each end of said shovel, one of said ropes being 80 adapted to serve as a haul rope, and a cable 85 coöperating with the other of said ropes and the shovel to preclude said shovel from dumping during transportation of the load.

8. In an excavating system, a track, a carriage adapted to travel thereon, a shovel, a cable for supporting the shovel and coöperating with the carriage, and a shovel hauling cable adapted to exert lateral tension on the supporting cable so as to change the normal angle of the latter with reference to the track, whereby movement is imparted to the carriage.

9. In an excavating system, an aerial track, a carriage adapted to travel thereon, a fall rope, a shovel suspended from the carriage by the fall rope, a haul rope for loading the shovel and hauling the carriage, and means separate from the fall rope and the haul rope for retaining the carriage in a substantially fixed relation to the aerial 100 track.

10. In an excavating system, a flexible track cable, a carriage adapted to travel thereon, a shovel suspended from the carriage, a haul cable for loading the shovel 110 and hauling the carriage, and means independent of the haul cable for retaining the carriage in a substantially fixed relation to the track cable.

In testimony whereof I have signed my 115 name to this specification in the presence of two subscribing witnesses.

CHARLES A. MORRIS.
